UNITED STATES PATENT OFFICE

104,087

DESIGN FOR A TELEPHONE DESK STAND

Henry E. Billington, Park Ridge, Ill., assignor to Kellogg Switchboard & Supply Company, Chicago, Ill., a corporation of Illinois

Application March 30, 1936, Serial No. 61,867

Term of patent 14 years

To all whom it may concern:

Be it known that I, Henry E. Billington, a citizen of the United States of America, residing in Park Ridge, county of Cook and State of Illinois, have invented a new, original, and ornamental Design for a Telephone Desk Stand, of which the following is a specification, reference being had to the accompanying drawing, forming a part thereof.

Fig. 1 is a side view of the telephone desk stand;

Fig. 2 is a plan view of the stand; and

Fig. 3 is an end view.

I claim:

The ornamental design for a telephone desk stand substantially as shown.

HENRY E. BILLINGTON.
